CHICAGO FORGING & MANUFACTURING CO., OF CHICAGO, ILLINOIS, A CORPORATION
OF ILLINOIS

HOOD LATCH

Application filed January 6, 1930. Serial No. 418,834.

Our invention relates to an improvement in automobile locking means for automobile hoods. It has for one purpose the provision of locking means for the hinged portion of the hood which shall be effective and shall prevent rattling and shall take up looseness or play. Another object is the provision of means for actuating such locking means in response to actuation of an exterior handle, which handle shall also be adaptable to raise and lower the hinged portion of the hood. Other objects will appear from time to time in the course of the specification and claims.

We illustrate our invention more or less diagrammatically in the accompanying drawings, wherein—

Figure 1 is a side elevation;

Figure 2 is an inside view on an enlarged scale;

Figure 3 is a detail;

Figure 4 is a section on the line 4—4 of Figure 2;

Figure 5 is a section on the line 5—5 of Figure 2;

Figure 6 is a section on the line 6—6 of Figure 2;

Figure 7 is a side elevation; and

Figure 8 is a front elevation of a variant form of locking abutment.

Like parts are indicated by like symbols throughout the specification and drawings.

Referring to the drawings, A generally indicates the longitudinal frame members of an automobile. A¹ is the radiator, A² the upper portion of the hood and A³ the lower hinged portion of the automobile hood. A⁴ indicates an inner abutment for the lower edge of the hinged hood portion A³. Rotatably mounted on the inner face of the hood portion A³ is a rock shaft generally indicated as B. The rock shaft includes a central offset portion B¹, terminal offset portions or crank hooks B² and additional offset portions B³. We may provide terminal bearing straps B⁴ adjacent the hook members B². Adjacent the central offset portion B¹ is a bearing structure assembly which includes the plate B⁵, secured to the inner face of the hood. It carries bearing members B⁶ B⁶, for

upper edge is formed with an inwardly turned flange B⁷ which may be slotted as at B⁸.

Rotatably mounted in relation to the plate B⁵ and the adjacent portion of the hood A³ is the exterior handle C which includes a portion C¹ projecting inwardly through the hood and the plate B⁵. The portions C¹ may be squared as at C² to receive the crank arm C³, shown in the form of a channel. The crank arm C³ is of such length as to penetrate with its outer end the slot B⁸, as shown in the full line position at the right of Figure 2. The portion of the crank arm and the slot B⁸ is such that rotation of the crank arm is limited when it passes beyond the center or beyond a vertical line drawn upwardly through its center of rotation. Mounted on the crank arm C³ is any suitable crank pin C⁴ pivoted to which is the connector member C⁵. As shown for example in Figure 5 this connector C⁵ constrains the offset portion B¹ of the rock shaft to position in contact with, or adjacent to, or in operative relation with the pin C⁴. B¹⁰ is any suitable stop for limiting the rotation of the crank arm C³ at the opposite limit of its movement.

As abutments for the end of the crank shaft, opposed to the crank members or hooks B², we illustrate yielding members which may include base portions D, secured to the automobile frame and more or less flexible members D¹ extending therefrom and terminating in the inclined portions D², opposed to the cranks B², and upwardly and inwardly inclined in relation to the lower edge of the hood. For example in Figures 2 and 4 we illustrate these abutments as formed of rod stock. They may be formed of any other suitable stock. We illustrate, for example, in Figures 7 and 8 generally similar abutments of strip spring stock.

It will be realized that whereas we have described and shown a practical and operative device, nevertheless many changes might be made in the size, shape, number and disposition of parts without departing from the spirit of our invention. We therefore wish our description and drawings to be taken as in a broad sense illustrative and di-

grammatic rather than limiting us to our specific showing.

The use and operation of our invention are as follows:

- 5 In the employment of the locking means for automobile hoods herein shown the manual handle C is in the horizontal position in which it is shown in Figure 1, when the rock shaft B is in full locking position, and when 10 it is in full unlocking position, the arc of rotation of the handle and of the crank arm C² being approximately 180°. When the handle has been rotated to bring the crank shaft C² into the full line position of Figure 15 2 the rock shaft is rotated with the terminal cranks or hooks B² in the position in which they are shown at the left of Figure 2, in locking engagement with the inclined abutment portions D². Preferably but not necessarily 20 these abutments are yieldingly formed. The cranks B² are to some extent yielding. In practice, it is often important that the cranks, such as B², be more yielding than would be a more rigid type of crank, such as a mere 25 radial extension at right angles to the crank. In employing the term "yielding" in connection with a crank, applicants wish to be understood as meaning a crank more yielding than would be a mere radial extension of the 30 material of the shaft. In employing an open loop, such as the recurved end portion B², we obtain a crank of satisfactory yielding characteristics as to flexure and torque. In order to provide a ready and automatic take-up, 35 and to compensate for wear and for variations in dimensions of the opposed parts and for irregularities in assembly and in location of parts, we provide for additional torsional take-up means. For example we provide additional offset portions B³ of the rock shaft. 40 These have the function of permitting the rock shaft to adjust itself torsionally to variations in positions of the opposed locking members. Enough spring or play is therefore provided to compensate for wear and to 45 compensate for example in irregularities in size, or shape of the abutments or of the crank members B² themselves.

In rotating the crank shaft the crank pin 50 C⁴ when rotating in one direction directly engages and actually moves the offset central portion B¹. In retrograde rotation the operation connection between the crank pin C⁴ and the offset B¹ is maintained by the pivoted connector C⁵. The slot B⁸ is so proportioned as to permit the crank arm C³ to override its center. This, taken in connection with the torsion of the shaft, serves to maintain it locked in position.

55 Co We claim:

1. A latching device for the hinged section of an automobile hood, which includes a rock shaft mounted on the inner face of the hood, a plurality of yielding latch abutments positioned within and spaced laterally inwardly

from the hood, offset portions associated with the rock shaft, adapted for engagement with said abutments, said abutments including upwardly and inwardly inclined relatively extended cam portions along which the offset portions of the rock shaft are slidably, and means for rotating said rock shaft, including an additional offset portion intermediate the ends of the shaft, a handle mounted on the hood, and an actuating connection between said handle and said last mentioned intermediate offset.

2. A latching device for the hinged section of an automobile hood, which includes a rock shaft mounted on the inner face of the hood, a plurality of latch abutments positioned within and spaced laterally inwardly from the hood, cranks associated with the rock shaft, adapted for engagement with said abutments, and means for rotating said rock shaft, including an additional crank intermediate the ends of the shaft, a handle mounted on the hood, and an actuating connection between said handle and said last mentioned crank, and means, intermediate said actuating connection and the latch abutment engaging cranks, for increasing the torsional yield of said shaft.

3. A latching device for the hinged section of an automobile hood, which includes a rock shaft mounted on the inner face of the hood, a plurality of latch abutments positioned within and spaced laterally inwardly from the hood, cranks associated with the rock shaft, adapted for engagement with said abutments, and means for rotating said rock shaft, including an additional crank intermediate the ends of the shaft, a handle mounted on the hood, and an actuating connection between said handle and said last mentioned crank, and means, intermediate said actuating connection and the latch abutment engaging cranks, for increasing the torsional yield of said shaft, including additional offsets in said shaft.

4. A latching device for the hinged section of an automobile hood, which includes a rock shaft rotatably mounted on the inner face of the hood, means, including a portion positioned exteriorly of said hood, for rotating said rock shaft, yielding crank elements associated with said rock shaft and yielding abutments positioned within and spaced laterally inwardly from said hood, adapted for engagement with said yielding crank elements, said abutments including upwardly and inwardly inclined and relatively extended cam portions along which the cranks are slidably positioned in camming relationship, when the rock shaft is moved into locking position.

5. A latching device for the hinged section of an automobile hood, which includes a rock shaft rotatably mounted on the inner face of the hood, means for rotating it, crank mem-

bers associated with the rock shaft, and yielding abutments, positioned within the hood, adapted to be engaged by said crank members, said abutments including each a base portion adapted to be secured to an automobile and a yielding cam member projecting therefrom along which said crank members are adapted to slide, in camming relationship, in response to rotation of the shaft into locking position, said cam member including a portion upwardly and inwardly inclined in relation to the lower edge of the hood.

6. A latching device for an automobile hood which includes a plurality of latch abutments within the hood and laterally inwardly spaced therefrom when the hood is in closed position, a rock shaft adapted to be supported upon the interior of said hood, said shaft having an intermediate crank, an actuating member, adapted to actuate said crank, rotatably mounted within and upon the hood, an exterior handle adapted to rotate said actuating member, and additional cranks on said shaft adapted to engage said latch abutments, and bearings interposed between the ends of the rock shaft and the hood, the ends of the rock shaft, adjacent said last mentioned bearings, being recurved toward the intermediate portion of the shaft, to engage said latch abutments.

7. A latching device for an automobile hood which includes a plurality of latch abutments positioned within the hood and laterally inwardly spaced therefrom when the hood is in closed position, a rock shaft adapted to be supported upon the interior of the hood, and means for rotating it, and offset recurved end portions on said rock shaft adapted to engage said latch abutments, said abutments being provided with surfaces, upwardly and inwardly inclined from the plane of rest of the hood, adapted slidably to receive the offset recurved portions of the rock shaft when they are rotated into locking position, said recurved ends being adapted to engage said inclined surfaces in sliding camming relationship.

8. A latching device for an automobile hood which includes a plurality of latch abutments positioned within the hood and laterally inwardly spaced therefrom when the hood is in closed position, a resilient rock shaft adapted to be supported upon the interior of the hood, the ends of said rock shaft being recurved toward the intermediate portion of the shaft, the recurved portions being generally parallel with the axis of rotation of the shaft, and being radially spaced therefrom, the portions of the shaft adjacent said recurved ends being secured rotatably to said hood and being aligned with said latch abutments, and means for rotating said rock shaft to thrust said recurved ends into camming

latching engagement with said latch abutments.

9. A latching device for the hinged section of an automobile hood, which includes a rock shaft mounted on the inner face of the hood, a plurality of latch abutments positioned within and spaced laterally inwardly from the hood, cranks associated with the rock shaft, adapted for engagement with said abutments, and means for rotating said rock shaft, including an additional crank intermediate the ends of the shaft, a handle mounted on the hood, and an actuating connection between said handle and said last mentioned crank, and means, intermediate said actuating connection and the latch abutment engaging cranks, for increasing the torsional yield of said shaft, including offset portions of the shaft extending outwardly from the axis of rotation of the shaft for a portion of the length of the shaft, said offset portions connecting portions of the shaft lying in the axis of rotation of the shaft.

Signed at Chicago, county of Cook and State of Illinois, this 27th day of November, 1929.
